SALT BATH FURNACE

Joseph Darius Griffin, Johannesburg, Transvaal,
South AfricaApplication August 1, 1939, Serial No. 287,725
In the Union of South Africa February 22, 1939

20 Claims. (Cl. 13—23)

This invention relates to salt bath furnaces and particularly, those arranged for heating the ends of rod-like bodies such as rock drilling tools and other bodies adapted to be suspended with a portion extending into the salt bath of the furnace.

Among the important objects of the present invention are to increase the capacity of the furnace by permitting the continuous movement of a series of articles through the bath; to provide for the proper preheating of the articles before entering the bath; to insure the immersing of the articles to a predetermined and accurately controlled extent; to provide for the progressive increase in the temperature of the bath along the path of movement of the articles; to increase the volumetric efficiency of the bath; and to accomplish various other objects which will be apparent from the drawings and the following description or which will be later pointed out.

In carrying out my invention, I provide means which defines the path for a series of articles and along which said articles may be moved while immersed to the desired extent in the bath so that the articles enter the furnace at one part thereof, are heated to the desired temperature during movement along the path and emerge at the properly heated temperature. The bath is formed of a salt which is solid at atmospheric temperature and which is heated and kept molten as, for instance, by the passage of an electric current flowing through the bath. The articles are preferably moved in a direction at right angles to the direction of current flow between the electrodes, and the heating may be to a different degree at the part of the bath from which the articles are withdrawn than it is in the part of the bath at which they are introduced.

The electrodes may be spaced apart to a distance only slightly greater than the width of the articles to be heated so that the articles may move along between the electrodes and these articles may be spaced very closely together so that the minimum size of bath may be employed for treating the maximum number of articles in a given time. Two parallel baths or bath sections may be formed by the use of three electrodes, or by only two electrodes if one constitutes the wall of the receptacle for the salt bath, so that the potential in the two paths or path sections may be maintained equal and thus, if the articles are electrically conductive, it is not necessary that they be insulated or even separated from one another in the line of travel or between the two path sections.

Preferably, arrangement is made whereby the series of articles pass through the bath at a constant speed such that the time period within which each remains in the bath is that required to bring it to the desired temperature. As the temperature of the article will not exceed the temperature of the bath, and as the temperature of the bath may be readily maintained constant, it will be apparent that a slower movement of the articles does not result in any overheating. By continuously immersing fresh articles to the bath at the inlet end of the path and simultaneously discharging heated articles from the other end of the path, and by having the articles closely spaced, the useful throughput of the bath is greatly increased while the cost of operation and upkeep of the furnace per article drops almost proportionally to the increase in the number of articles immersed simultaneously because only a small portion of the heat taken up by the salts is utilized in heating the metal parts immersed within the bath.

Furthermore, the uniform loading of the bath makes it unnecessary to provide a large depth of salts below the point to which the articles are immersed, and which has heretofore been considered necessary for the storage of heat and to avoid temperature fluctuations with variations in working conditions.

Although the present invention may be employed for the heating of various articles, certain features of the invention are of special importance in connection with the heating of rock drill tools which ordinarily have a longitudinal passage therethrough. Upon the insertion of the end of such a rock drill tool directly from atmospheric temperature into the molten bath, the air in the central passage is heated extremely rapidly and in rushing out from the upper end of the tool creates a suction which draws the molten salt up into the passage where it may solidify or may even spurt from the upper end of the tool with liability of serious burning of operators.

As a feature of my invention, the tools before immersion in the molten salt are temporarily held above the level of the salt or in an adjacent extension of the furnace, so that they become rapidly preheated from the air or gases in or blowing out of the furnace and the close proximity to the bath and therefore, when they do enter the bath, the air within the central passage has already become heated and expanded and there is no suction effect and no liability of drawing molten salt up into the passage.

As an important feature of the invention, there is provided a conveying means which moves the articles along the predetermined path and which lowers them into the bath to the predetermined extent only after they have had a sufficient time interval to become properly heated.

As a further important feature, there are provided spacers between the articles to hold them in the proper spaced relationship and at the same time to effectively close the top of the furnace and prevent escape of heat. Preferably, the top of the furnace is spaced to some distance above the level of the bath, the articles or the suspending means therefor pass along a comparatively narrow slot in the roof which is effectively closed by the spacers, and the movement of the articles along the bath is effected by a conveyor above the roof which controls the elevation of the articles and not only moves the articles but through them, moves the spacers.

In the accompanying drawings, there are shown several different forms in which various features of my invention may be incorporated. In these drawings,

Fig. 1 is a top plan view showing the parts somewhat conventionally illustrating the parts and the rock drill tools being shown in section;

Fig. 2 is a vertical longitudinal section on the line 2—2 of Fig. 1;

Figs. 3 and 4 are transverse sections on the lines 3—3 and 4—4 respectively of Fig. 2;

Fig. 5 is a vertical section on the line 5—5 of Fig. 2;

Fig. 6 is a view somewhat similar to Fig. 2 but more diagrammatically showing another form with one electrode on the bottom and the articles serving as the other electrode;

Fig. 7 is a somewhat diagrammatic top plan view of an apparatus arranged with two parallel baths;

Fig. 8 is a vertical section through a furnace having two bath sections.

Fig. 9 is a top plan view of a further form in which there is a single endless bath with the articles inserted and withdrawn at the same point in the bath;

Fig. 10 is a somewhat diagrammatic view similar to a portion of Fig. 8 but showing a wiring diagram and another means for connecting the current to the electrodes;

Fig. 11 is a sectional detail showing how the electrodes may be mounted in the wall of the furnace;

Fig. 12 is a top plan view of another type of furnace in which the preheating feature of my invention may be carried out; and

Fig. 13 is a section on the line 13—13 of Fig. 12.

In the specific form illustrated in Figs. 1 to 5 inclusive, there is provided a furnace 10 adapted to hold the salts constituting the bath. The walls of the furnace are of heat insulating material and of a character which will not be adversely affected by the molten salts. These walls are shown only diagrammatically as it will be understood that in practice, they are very much thicker and of such thickness and with such insulating spaces as to conserve the heat and prevent any substantial amount of radiation to the outside atmosphere.

The chamber for the bath is formed of a length sufficient to permit of the proper heating of the articles while traveling lengthwise thereof and is preferably of a width only slightly greater than the maximum width of the portions of the articles inserted in the bath. In this form there

are shown electrodes 11 and 12 set into the inner surfaces of the opposite side walls and parallel to each other and parallel to the direction of travel of the articles. Each electrode may, if desired, be made up of separate sections as shown at 11 and 11a in Fig. 2 so that there will be the minimum liability of buckling or displacement due to temperature changes.

The electrodes may be mounted as shown in Fig. 11, that is, the bottom edge may be slightly tapered and rest against inclined surface 13 so that as the electrode progressively becomes thinner from corrosion during use, it may be raised slightly from time to time and have its face brought back to the proper plane and packing 14a inserted in the rear. To start with, the thickness of the electrode may be equal to the depth of the recess and no packing or space for packing would be present.

I have not illustrated any means for efficiently heating the salts to bring them to the molten condition, but this may be done by any conventional means commonly employed in connection with salt bath furnaces. The alternating current of the desired potential and current strength may be conducted to the electrodes in any suitable manner as for instance, by bus bars 14 secured to flanges 15, extending out through opposite walls of the furnace.

The furnace is provided with a cover 16 which may be removed for cleaning, for adjustment of the electrodes or for other purposes. This cover has a slot 17 in the top thereof which is of a width only slightly greater than the diameter of the rods or the other suspending means for the articles or parts to be heated. The ordinary rock drill tool has a shank A with a central passage B therethrough and a cutting head C at one end thereof and larger than the shank. For the treatment of such articles, the slot 17 and the cover have enlarged portions 18 at the ends thereof which are of sufficient size to permit the insertion and withdrawal of the tools.

Above the cover 16 there is provided an endless conveyor 19 which may be in the form of a pair of chains mounted on sprocket wheels 20 driven in any suitable manner and at the desired speed. The upper runs of the two parallel chains serve to support the articles at the desired elevation. The supporting means which also provides for the desired vertical positioning or adjustment of the articles may be in the form of clips 21 which are secured to the shanks of the drills, or onto other suspending means with one end of each clip resting on one chain, and the other end resting upon the opposite chain. Each may carry a pair of semi-circular liner sections for directly engaging the shank and these may be of insulating material to prevent transfer of current to any drill to another or from the conveyor mechanism. The clips are preferably so formed that they directly contact one with another and thus hold the articles in the desired spacing.

The conveyor chains may be of any suitable construction but preferably include rollers which are supported upon track members 22 so that the weight of the upper runs of the chains as well as the articles are supported by the track members. These track members may be supported in any suitable manner as for instance, by brackets 23 secured to the opposite walls of the furnace and vertically adjustable so as to vary the elevation of the brackets in respect to the top of the furnace or the surface of the molten bath. In Fig. 2 this adjusting means is shown some-

what diagrammatically as vertical slots in the base portions of each bracket and through which the clipping bolts are secured.

The upper side of each track is preferably arranged so that the elevation of the tools will be changed during the movement of the articles along the bath. As shown in Fig. 2, the upper edge of the right hand portion of the track 22 is downwardly inclined for a short distance so that when the article is inserted to the position controlled by the location of the clip thereon, the lower end of the article will be slightly above the liquid level of the bath. Thus, the lower end becomes heated before contacting with the bath and the air inside of the lower end of the article may be likewise heated so that there will be little or no further expansion of this portion of the air after the lower end of the central passage is closed by the entry of the article into the bath. The major portion of the upper edge of the track 22 is substantially parallel with the liquid level so that the articles, as they move along, are inserted to a predetermined and substantially uniform distance into the bath. If desired, the portion of the upper surface of the track nearer the point of discharge for the articles may be inclined upwardly so that the lower ends of the articles will be partially withdrawn from the bath, or held close to the surface thereof during the final portion of the movement to the point of discharge. One operator may continuously feed successive articles through the opening 18 at one end of the bath and at the rate at which the conveyor is traveling, while another operator may progressively move the articles from the furnace at the other end of the bath.

In order to conserve the heat within the bath, there are provided a series of spacers 25 which rest upon the top of the cover 16 and effectively close the slot 17 in the latter. These spacers are of a width substantially equal to the center line spacing of the articles and have notches or recesses in opposite sides to form openings snugly fitting the articles or the suspending means for the latter. Thus, the entire top of the slot is closed by the series of spacers and the operator who feeds in the articles at one end applies a spacer to the cover for each article as he inserts it and supports it on the conveyor. As later pointed out, the spacers may form the cover so that no slot would be employed.

As the articles are moved along by the conveyor, the spacers are simultaneously slid along the cover, and as each article is removed the spacer adjacent thereto may drop into a receiver 26 at the end of the furnace. These spacers are from time to time taken around to the other end of the furnace and one is put in place for each article inserted in the bath. The spacers may be of any suitable material but preferably, of heat insulating material, but they do not need to have any very great strength because they do not carry any load and are merely slid along by the articles. The spacers not only conserve the heat but prevent fumes or gases escaping from the top of the furnace where they might be injurious to the workmen. To permit of the withdrawal of such fumes or gases, the furnace at one end may be provided with a gas outlet conduit 27 which may extend to any point of disposal of the gases or may be connected to a blower for continuously withdrawing such gases.

It is important that the level of the bath be maintained substantially constant. As the level

of the liquid may change upon the insertion of the articles and may be on a slightly different elevation according to the number of articles inserted, or the degree of insertion, or the size of the articles, there is preferably provided an overflow chamber 28 into which excess liquid from the bath may overflow a sharp edge weir 29, and further salt may be continuously or intermittently fed to the bath to insure the maintenance of the level up to the top of the weir.

It is desirable that the bath be maintained at a somewhat higher temperature near the point of discharge of the articles than at the point of insertion. This may be accomplished in various ways. As shown in Fig. 2, the electrodes 11 and 11a are inclined at their lower ends so that the electrode area per lineal foot along the length of the bath is greater at the discharge end than it is at the entrance end. The larger the immersed surface of the electrode at any part of the bath, the larger is the amount of current which will be discharged through the bath to heat that part. Other means for accomplishing this result will be pointed out hereinafter.

In order to impede convection currents which might tend to keep the bath of uniform temperature at opposite ends, there may be provided one or more transverse partitions 30, the upper edges of which terminate below the level to which the articles are to be inserted. If the electrodes be each formed of a series of sections, then these insulating transverse partitions may be disposed between adjacent sections of the electrodes. The electrodes are preferably spaced to some distance above the bottom of the furnace and this bottom may be inclined from one end to the other so that slag which collects at the bottom of the furnace, either from dirt or oxide coming in with the articles or from any other source, can be accumulated at a low point from which it may be withdrawn by a scoop or any other convenient means. The bottom may also taper toward the center to form a narrow channel or trough 32 as shown in transverse section in Fig. 5 for the same purpose.

As the salt removal by a plurality of articles from the bath will tend to lower the liquid level, particularly when the bath surface is very small at the top, it is desirable to provide means for increasing the surface area at the top of the bath so as to minimize such changes in liquid level. As shown in Fig. 4, the bath at one end and preferably at the discharge end is provided with one or more laterally extending sections 33. These may be of any desired shape and on either or both sides, and of an area dependent upon the area of the surface of the bath along the path of the articles and the extent to which the articles are immersed in the bath. These lateral extensions do not need to extend down to the bottom of the bath, but may be only at the upper part thereof.

Various different means may be employed for varying the heating effect at different points of the bath so that the bath will be the hottest at the point where the articles are withdrawn. Also, various different constructions and arrangements of electrodes may be employed. In Fig. 6, there is shown a construction in which most of the parts are substantially as above described, but there is provided an electrode 11b which is inclined in respect to the surface level of the bath and the articles constitute the other electrode. At the entrance end the electrode is at the greatest distance from the articles and there-

fore, there will be a higher resistance to current flow and a lower amount of current and a lesser heating effect than at the discharge end where the electrode is comparatively close to the articles forming the other electrode. The current may be conducted to the articles in any suitable manner as for instance, by connection to the guide rail 22 which may be in electrical connection with the articles through the conveyor and clips 21.

It is not essential that the path be a straight one and there are certain advantages in making the path annular so that one operator may remove heated articles and insert fresh ones at the same point in the bath. In Fig. 9, I have shown a furnace 10c which has an annular slot 11c with a single enlarged portion or hole 18c. In this case there may be provided a central electrode 11c and the wall of the furnace may constitute the other electrode. In order to keep the slot closed at all points except at the hole 18c, the spacers 25c may be tapered radially toward the center of the curved portions of the path so that they will abut and not overlap in passing around the curve and will keep the slot covered.

In Fig. 7, there is shown somewhat diagrammatically a construction in which there are two parallel slots 17d so that two series of articles may be advanced simultaneously. In such a construction, there may be provided a pair of electrodes 11d and 12d on the opposite walls and a central electrode 11' dividing the bath into two portions as shown in Fig. 8. By using a three-phase circuit and connecting one conductor to the central electrode and the other two conductors to the side electrodes, the potential across the two bath portions will be maintained equal and it will not be necessary to insulate the articles from each other, or from the conveyor or other parts.

It is not essential that the cover, as shown in Figs. 1 to 5 inclusive and Fig. 7, be provided with slots. The entire cover in the form shown in Figs. 1 to 5 inclusive may be formed by the spacers 25 which may rest directly upon the furnace wall. This arrangement is shown in Fig. 8 where the spacers 25d each have two notches in each side thereof instead of only one and rest directly on the side walls. In this case the spacers may be made of stiffer and stronger material and may serve as the means for supporting the articles themselves. The clips 21d which are secured to the articles may rest directly upon the spacer sections 25d and move along with them.

In the form shown in Figs. 7 and 8, the same general type of conveyor mechanism hereinbefore described may be employed with means for varying the elevation of the articles at different points in the path. When the spacers support the articles to be heated, the surfaces on which the spacers rest must be varied in height relative to the salt level in order to vary the elevation of the articles as these surfaces then serve the same purpose as the track members 22.

In Fig. 10 there is illustrated somewhat diagrammatically a construction in which the spacers 25e constitute the top wall as in Fig. 8, but in which the articles serve as the electrodes. As the articles move along, the effective delivery of current to the articles may be accomplished by the use of troughs 40 along the sides of the furnace and containing mercury. The two troughs may be connected by conductors 41 to two of the wires of a three-phase circuit, and each article may have a clip 21e electrically connected

thereto and provided with a conductor 42 extending into and movable along the trough of mercury so that the flow of current to the electrodes will be insured during the movement of the electrodes through the bath.

The furnace may be provided with a central electrode 43 connected to the other wire of the three-phase system so that the current will flow between the central electrode and both rows of articles. This furnace is also shown as provided with side electrodes as in Fig. 8 so that the conductors 41 might be connected to the side electrodes instead of to the articles themselves.

Although my invention is particularly applicable for the simultaneous heating of a series of articles, it will be obvious that the apparatus may be employed for heating of only one article at a time. Obviously, the heating effect on each article will be the same and the apparatus will operate the same with only one article in the bath as it will with a series. Even with only a single article being heated at one time, the apparatus has the advantage of delayed immersion and different temperatures at opposite ends of the path.

The delayed immersion feature of my invention may be employed in connection with furnaces where the articles are not progressively moved through the bath. In Figs. 12 and 13 I have shown a furnace 45 having a molten salt bath 46, a horizontal electrode 47 on the bottom, and electrical connections to the articles A to be heated. The cover 48 is shown as provided with a plurality of holes through which articles may be inserted to the required distance and immersed to the desired extent. With such a furnace, one of the articles may be inserted, first, to a point slightly above the bath so that it becomes pre-heated, and after being held in that position for the required time, may be immersed to the desired distance in the bath.

Such a small furnace might be used for heating a small number of articles so that when an article is removed from one hole in the cover, another one may be inserted, first, to the pre-heating point, and then into the bath, and another one of the articles removed after being heated and replaced by another. As many holes would be provided in the apparatus as required so that the articles may be removed in succession and each one heated to the proper temperature before removal.

Having thus described my invention, what I claim as new and desire to secure by Letters Patent is:

1. The method of heating the ends of rod-like bodies such as rock drill tools, which includes maintaining a salt bath by the direct passage of electric current through the bath material between spaced electrodes, vertically suspending the rod-like bodies with their lower ends immersed in the bath, and moving the series of bodies along a path such that their lower ends follow a substantially equipotential line in the bath.

2. The method of heating the cutting head of a hollow rock drill tool, which includes suspending the tool vertically with its head adjacent to but spaced above a molten salt bath, and thereafter immersing the end of the drill in said bath to heat it to substantially the temperature of the bath, the spacing of the drill head in respect to the surface of the molten salt bath and the time during which the tool is so suspended being such that the air within the lower end of the tool

becomes heated to a high temperature, greatly expanded, and flows out before said head is immersed, whereby the further heating of the air in said body, after immersion, does not cause such further expansion and upflow of air in the body as will suck molten liquid from said bath up into the body to a level substantially above the level of the bath.

3. The method of heating rod-like bodies such as rock drill tools by means of a salt bath furnace heated by the flow of electric current through the bath material between parallel electrodes, which method includes immersing the ends of the bodies into the bath to a limited distance below the top surface thereof, and progressively moving said bodies through the bath in a direction substantially parallel to the opposed electrodes.

4. The method of heating rod-like bodies such as rock drill tools, which includes electrically heating a bath of molten salt by the direct passage of current transversely therethrough, the volume of current passing through the bath being greater at one end than at the other to maintain a higher temperature at one end than at the other, immersing the ends of said bodies into said bath, and progressively moving said bodies through said bath from the portion at lower temperature to the portion at higher temperature while maintaining the degree of immersion of said ends substantially constant.

5. The method of heating rod-like bodies such as rock drill tools, which includes maintaining a heated bath of molten salt by the direct passage of current transversely therethrough, the volume of current passing through the bath being greater at one end than at the other to maintain a higher temperature at one end than at the other, immersing the ends of said bodies into said bath, progressively moving said bodies through said bath from the portion at lower temperature to the portion at higher temperature while maintaining the degree of immersion of said ends substantially constant, and inhibiting the flow of convection currents in said bath from one end toward the other.

6. The method of heating the ends of rod-like bodies such as rock drills by means of a salt bath furnace heated by the flow of electric current through the bath material between spaced electrodes, which method includes progressively and continuously moving a series of said bodies along a path lengthwise of the bath and transverse to the direction of current flow, holding the ends of said bodies at a short distance above the bath along the initial portion of the path to preheat the ends by the gases from said bath, and maintaining said ends immersed in the bath to a predetermined distance while moving along another portion of said path.

7. The method of heating the cutting ends of a series of rock drill tools each having a central passage, which includes maintaining a molten salt bath, moving said tools lengthwise of said bath, maintaining the cutting ends at a short distance above the level of the bath along a portion of said path to permit heating and expansion of the air within the central passages of the tools, and maintaining the cutting ends immersed to a predetermined distance in the bath during a further portion of the path of movement.

8. A salt bath furnace comprising a chamber for the bath material, spaced electrodes for heating said material by the passage of an electric current between electrodes and through the intervening bath material, and a conveyor arranged

for moving a series of articles to be heated through the bath in a path following substantially an equipotential line between the electrodes.

9. A salt bath furnace comprising a chamber for the bath material, electrodes upon opposite sides of said chamber and spaced apart to a distance but little greater than the width of the articles to be heated, and a conveyor for moving the articles with portions only thereof immersed in the bath and in a direction transverse to the flow of current between said electrodes.

10. A salt bath furnace comprising a chamber for the bath material, electrodes upon opposite sides thereof for heating the material by passing an electric current transversely through the bath material, a conveyor above said chamber for moving the articles a short distance lengthwise of the bath and above the latter, and thence partially immersing the articles in the bath and continuing the movement through the bath.

11. A salt bath furnace having a chamber for the bath material, electrodes for heating the material by the passage of an electric current therethrough, a pair of endless conveyors disposed in parallel vertical planes above the path, with horizontal runs adapted to support articles suspended therefrom and partially immersed in the bath.

12. A salt bath furnace including a chamber for the bath material, electrodes for heating said material by the passage of an electric current between said electrodes through the bath material, means for supporting a series of rock drill tools with their lower ends immersed in said bath and for moving them lengthwise of the bath, the width of said bath being only slightly greater than the width of the portions of said tools immersed therein.

13. An electrically heated salt bath furnace comprising a bath chamber, a conveyor arranged for vertically suspending a series of bodies such as rock drill tools and moving said bodies in a substantially horizontal direction with their lower ends immersed in said bath, and a series of spacers slideable along the top of said bath and substantially closing said chamber, said spacers being moved by said conveyor through contact of said bodies with said spacers.

14. A salt bath furnace including a bath chamber, a conveyor for vertically suspending a series of bodies such as rock drill tools and moving said series in a substantially horizontal direction with the lower ends of the bodies extending into the bath, an auxiliary reservoir and a weir over which the bath material may flow to said reservoir to maintain a substantially constant level within said bath.

15. A salt bath furnace having a bath chamber, electrodes therein and upon opposite sides thereof, said electrodes being adjustable toward and from each other, and means for supporting a series of articles with their lower ends immersed in the bath and conveying them through the bath between and substantially parallel to said electrodes.

16. A salt bath furnace comprising a bath chamber, electrodes upon opposite sides thereof, said electrodes being wider at one end of the bath than at the other, and means for supporting a series of articles with their lower ends extending into said bath and conveying them lengthwise of the bath from a point adjacent to the narrower end of said electrodes to a point adjacent to the wider end of said electrodes whereby the bath and articles are progressively heated to higher temperatures.

70

17. A salt bath furnace comprising a comparatively narrow long bath chamber having electrodes upon opposite sides thereof, and means for vertically suspending a series of articles and advancing them lengthwise of said chamber with their lower ends immersed in the bath, said chamber having an auxiliary reservoir portion adjacent to the bath level whereby the area of the surface of the bath is substantially larger than the portion of the bath along the path of travel of said articles.

18. A salt bath furnace comprising a bath chamber having a plurality of electrodes upon opposite sides thereof, the electrodes adjacent to one end of the bath being of larger surface area than those adjacent to the opposite end of the bath, and means for conveying a series of articles through said bath from the end having the smaller electrodes to the end having the larger electrodes.

19. A salt bath furnace having a comparatively narrow bath chamber, electrodes presenting increasing surface contact with the molten salt along the length of the bath from one end to the other, and means in said bath for inhibiting

transfer of molten salt from one section of the bath to another.

20. The method of heating the ends of hollow rod-like bodies such as rock drills by means of a salt bath furnace heated by the flow of electric current through the bath material between spaced electrodes, which method includes progressively and continuously moving a series of said bodies along a path lengthwise of the bath, holding the ends of said bodies at a short distance above the bath along the initial portion of the path to preheat the ends by heat radiated from said bath, and maintaining said ends immersed in the bath to a predetermined distance while moving along another portion of said path, the rate of movement of said bodies and the length of said initial portion of said path being such that the air within the lower ends of said bodies becomes heated to a high temperature, greatly expanded, and flows out before said ends are immersed, whereby the further expansion and upflow of air in said bodies after immersion, does not suck molten liquid from said bath up into the body, to a level substantially above the level of the bath.

JOSEPH DARIUS GRIFFIN.
